UNITED STATES PATENT OFFICE.

CHRISTIAN AALBORG, OF WILKINSBURG, PENNSYLVANIA, ASSIGNOR TO WESTINGHOUSE ELECTRIC AND MANUFACTURING COMPANY, A CORPORATION OF PENNSYLVANIA.

CIRCUIT-INTERRUPTER.

1,173,632.

Specification of Letters Patent. Patented Feb. 29, 1916.

Application filed June 28, 1911. Serial No. 635,910.

To all whom it may concern:

Be it known that I, CHRISTIAN AALBORG, a citizen of the United States, and a resident of Wilkinsburg, in the county of Allegheny and State of Pennsylvania, have invented a new and useful Improvement in Circuit-Interrupters, of which the following is a specification.

My invention relates to circuit interrupters, and it has special reference to interrupters of the resistance type that are adapted to handle very heavy currents and are provided with a plurality of interrupting devices by means of which the circuit is opened without injurious arcing or undue voltage surges on the circuit.

The object of my invention is to simplify and improve the construction and operation of devices of the above-indicated character and to provide a circuit interrupter which shall be rugged, compact and durable in construction, effective and reliable in operation and shall embody means for positively interconnecting the plurality of interrupting devices whereby a fixed and definite relationship is maintained between them and all possibility of opening in an improper order is precluded.

According to my invention, I provide a circuit-interrupting device which embodies a main current-carrying interrupting means and an auxiliary arcing interrupting means connected in multiple thereto and in series circuit with a plurality of resistor sections. The movable members of the several interrupting devices are suitably supported upon rods which are associated with the free ends of a plurality of operating levers, said levers being respectively connected to the arms of a pivotally mounted bell-crank lever by means of suitable links. By means of this mechanism, which will be hereinafter set forth in detail, the movable members of the several interrupting devices are positively interconnected and are, therefore, rendered interdependent.

My invention may best be understood by reference to the accompanying drawings, in which—

Figure 1 is a view partially in section and partially in side elevation, of a circuit interrupter constructed in accordance with my invention; Fig. 2 is an enlarged view, in elevation, of the operating mechanism

shown in Fig. 1; Fig. 3 is an enlarged plan view of the operating mechanism shown in Fig. 1; Fig. 4 is a diagrammatic view showing the circuit connections of the interrupter, and Figs. 5 and 6 are views in outline showing the relationship of certain parts of the operating mechanism in an intermediate position and in full open position, respectively.

Referring to the drawings, the circuit interrupting device comprises a liquid-containing tank 1, a main interrupting means 2 embodying a plurality of stationary current-carrying terminals 3 and a coöperating movable member 4, an auxiliary interrupting means 5 embodying a plurality of stationary arcing terminals 6 and a coöperating movable member 7, a plurality of resistor sections 8 associated with said auxiliary interrupting means 5, an insulated terminal member 9 for conducting electrical energy to said resistor sections 8 and interrupting means 2 and 5, a plurality of rods 10 and 11 for respectively supporting the movable members 4 and 7, an operating mechanism 12 for actuating said interrupting means in succession and in a predetermined order, a latch 13 for restraining the operating mechanism in its normally closed position, a tripping device 14 for releasing said latch under predetermined abnormal circuit conditions, a power-operated means 15 for closing or resetting the operating mechanism, and a cover or casing 16 for inclosing and protecting the operating mechanism.

The stationary contact terminals 3 and their coöperating switch member 4 constitute a low-resistance circuit which normally carries the total current and is adapted to effect the preliminary interruption thereof, as will be hereinafter set forth.

The auxiliary stationary contact terminals 6 are arranged in pairs, each of which is connected in series with a plurality of resistor sections 8 and with a portion of the coöperating movable switch member 7 and constitutes a high-resistance circuit which is connected in multiple relation with the low-resistance circuit. The final interruption of the circuit is accomplished through the interrupting means 5 which is associated with the high-resistance circuits just referred to, and, inasmuch as these circuits are required to carry the current only dur-

ing the short interval between the preliminary and final interruptions, the co-operating contact members may be designed and constructed without regard to current-carrying capacity and serve merely as arcing terminals.

Each of the resistor sections 8 comprises a plurality of vertically disposed grids 17 which are assembled side by side and suitably insulated from one another, said resistor sections being mounted above the several interrupting means and suitably secured to a supporting frame 18 which is suspended within the tank 1.

15 The operating mechanism 12 embodies a plurality of operating levers 19 and 20, the normal positions thereof being indicated respectively by the broken lines A and B in Figs. 2, 5 and 6. One end of each lever is 20 pivotally supported upon a shaft 21 and the free ends thereof are respectively associated with the rods 10 and 11 which support the movable members 4 and 7 of the several interrupting means. The shaft 21 25 is supported between upwardly projecting members 22 of a main supporting casting 23 which is suitably attached to the top of the liquid-containing tank 1, and serves to support the various parts of the operating 30 mechanism. A stop or bumper 24 is also provided upon the supporting member 23 and is adapted to engage a projecting portion 25 of the lever member 20 in order to limit the downward movement thereof.

35 A member 26 is pivoted upon a shaft 27 that is carried by an upwardly projecting member 28 which forms a part of the supporting casting 23, said member 26 comprising a plurality of arms 29, 30, 31 and 40 32. The respective arms 29 and 30 of the member 26 are normally disposed in substantially horizontal and vertical planes and constitute the arms of a bell-crank lever having its pivotal support upon the shaft 45 27, said arms being respectively connected to the operating levers 19 and 20 by means of links 33 and 34. It should be noted that the arm 30 normally assumes a position somewhat to the right of the vertical plane 50 passing through its pivotal support, while the arm 29 occupies a position slightly above the horizontal plane through its pivotal support, for a reason that will be hereinafter pointed out.

55 Between the arm 31 and the shaft 21 are connected two links 35 and 36 which form an operating toggle by means of which the bell crank lever or multi-arm 26 is forced into its normal position through the agency 60 of the power-operated means 15 and a connecting link 37, one end of which is suitably secured to the link 35 while the other end is similarly associated with a portion of the power-operated means 15.

65 A projection 38 is provided upon the link

35 to engage the latch member 13 which serves to hold the operating toggle in approximately a dead-center position. A horizontally projecting arm 39 forms an integral part of the latch member 13 and is so disposed, with relation to the tripping mechanism 14, that it may be engaged thereby, in the usual manner. A spring 40 is connected between the arm 39 of the latch member 13 and the supporting casting 70 23, whereby said latch is maintained in engagement with the projection 38.

In order to effect a counter-clockwise rotation of the bell-crank lever 26, and to 75 secure a positive and rapid action of the operating mechanism 12 when it is released from the latch 13, a heavy coil spring 41 is connected between the arm 32 of said bell-crank lever and a fixed pin 42. The tension of the spring 41 may be regulated 80 as desired by an adjusting nut 43, in the usual manner.

The tripping mechanism 14 may be of any well known construction and comprises 85 a stationary core 44, a movable core 45, an energizing coil 46, and a hammer rod 47 that is associated with the movable core 45 and is adapted to deliver a sudden blow to the arm 39 of the latch 13 under predetermined abnormal circuit conditions. 90 Obviously, any other suitable device for accomplishing the same purpose may be employed.

The power-operated means 15 is merely 95 illustrative of any suitable means for closing the circuit interrupter and forms no part of my invention, except as it performs a necessary function in its operation. As shown, the operating means 15 comprises a cylinder 48 and a movable piston 49 which 100 is disposed therein in the usual manner and is suitably associated with one end of the connecting link 37, said piston 49 being adapted to be actuated either pneumatically or hydraulically, as desired.

110 Assuming the various parts of the interrupter to occupy the positions shown in the drawings, and the tripping means to be energized in response to a predetermined abnormal circuit condition, the hammer rod 47 is 115 projected against the end of the arm 39, whereby the latch 13 is disengaged from the projecting portion 38 of the link 35. Thus, the operating toggle which comprises the links 35 and 36 is released and the bell- 120 crank lever 26 is rotated in a counter-clockwise direction by means of the spring 41 and the weight of the suspended parts. During the first part of the rotation of the bell-crank lever 26, the operating lever 19 and 125 its associated movable contact member 4 are lowered by reason of the substantially downward travel of the arm 29, while the operating lever 20 and its associated movable contact member 7 are maintained in substan- 130

tially their original positions because of the substantially horizontal travel of the arm 30. Thus, it is evident that the movable member 4 is disengaged from its coöperating contact terminals 3, and the main interrupting means 2 is therefore opened, while the auxiliary interrupting means 5 remains closed.

By referring particularly to Fig. 5, which shows the relationship of the various parts of the operating mechanism in an intermediate stage during its opening, when the arm 30 of the bell-crank lever 26 occupies a position which is the same distance to the left 15 of a vertical plane through its pivotal support as it originally occupied to the right thereof, the operation of the interrupting means and the interconnecting mechanism will be readily understood.

As the bell-crank lever 26 rotates beyond the position shown in Fig. 5, the operating lever 19 and its associated movable contact member 4 continues to be lowered for a short distance, after which they are raised slightly, 25 while the operating lever 20 and its associated movable contact member 5 are also lowered until the lever 20 engages the stop 24. In this position, the circuit interrupter is fully opened and the relationship of the 30 various parts of the operating mechanism is shown in Fig. 6.

Inasmuch as the arm 29 finally occupies a position slightly to the right of a vertical plane through its pivotal support, as shown 35 in Fig. 6, it is evident that the final position of the movable contact member 4 is not at its extreme lowest point of travel but that said member has been slightly raised from its lowermost position during the latter part of the operation, as will be readily understood.

By reason of the action of the operating mechanism, as hereinbefore explained, it is manifest that a preliminary interruption of 45 the circuit is effected through the main current-carrying interrupting means 2, whereby the current is caused to flow through the auxiliary high-resistance circuits in multiple thereto and is finally interrupted 50 through the agency of the auxiliary arcing interrupting means 5.

In order to close or reset the interrupter, an operating fluid is admitted into the cylinder 48 where it acts against the movable 55 piston 49, causing it to be raised and thereby exerting a pressure upon the link 35 which, with the link 36, constitutes the operating toggle. As the operating toggle is forced into its set position, the bell-crank lever 26 is rotated in a clockwise direction, whereby the respective interrupting means 5 and 2 are closed in succession and in the order named, as will be readily understood without further description. In the closed 60 position, the latch 18 engages the projection

38 on the link 35 and restrains the mechanism in the usual manner.

Although I have shown and described a circuit interrupter of specific construction, it will be understood that various modifications may be effected in its arrangement and location of parts and that such modifications as do not depart from the spirit and scope of my invention are intended to be covered by the appended claims.

I claim as my invention:

1. In a circuit interrupter, the combination with a plurality of stationary contact terminals and a plurality of coöperating switch members adapted to make engagement therewith, of a bell-crank lever having arms respectively disposed in substantially horizontal and vertical planes, and means for connecting the arms to the switch members.

2. In a circuit interrupter, the combination with a main and an auxiliary interrupting means, of a pivotally mounted bell-crank lever having arms respectively disposed in substantially horizontal and vertical planes, and means for connecting the said arms to the interrupting means whereby the movement of the bell-crank lever causes the sequential operation of the interrupting means.

3. In a circuit interrupter, the combination with a main and an auxiliary interrupting means, of a pivotally mounted bell-crank lever having arms respectively disposed in substantially horizontal and vertical planes, and links for connecting the said arms to the interrupting means whereby movement of the bell-crank lever causes sequential operation of the interrupting means.

4. In a circuit interrupter, the combination with a main and an auxiliary interrupting means, of a bell-crank lever having two arms disposed substantially at right angles, means for operatively connecting the main and the auxiliary interrupting means respective to the arms whereby movement of the bell-crank lever causes the interrupting means to operate in sequence.

5. In a circuit interrupter, the combination with a plurality of main stationary contact terminals, a switch member to coöperate therewith, a plurality of auxiliary contact terminals, a switch member to coöperate therewith, and sections of resistance connected in series circuit with said auxiliary terminals and switch member and in multiple to said main terminals and switch member, of a bell-crank lever having two arms disposed substantially at right angles to each other, said arms being positively connected to said switch members for actuating the auxiliary switch member subsequent to the main switch member.

6. In a circuit interrupter, the combination with main stationary contact terminals,

- 4
- a switch member coöperating therewith, a plurality of auxiliary contact terminals, a switch member therefor, and sections of resistance connected in series circuit with said auxiliary terminals and switch member and in multiple to said main terminals and switch member, of a plurality of operating levers severally associated with said switch members, and a pivotally mounted bell-crank lever having two arms disposed substantially at right angles to each other that are positively connected to the respective operating levers. 5
7. In a circuit interrupter, the combination with main stationary contact terminals, a switch member coöperating therewith, auxiliary stationary contact terminals, a switch member coöperating therewith, and sections of resistance connected in series circuit with said auxiliary terminals and switch member and in multiple circuit with said main terminals and switch member, of a bell crank lever having arms respectively projecting in substantially horizontal and vertical planes, positive means for respectively connecting said main switch member to said horizontally disposed arm and said auxiliary switch member to said vertically disposed arm. 10
8. In a circuit interrupter, the combination with a low-resistance circuit, interrupting means therefor, a plurality of high-resistance circuits connected in multiple thereto and interrupting means for said circuits, of a bell-crank lever having two arms disposed substantially at right angles to each other and operatively connected to said circuit interrupting means for actuating said means one after the other. 15
9. In a circuit interrupter, the combination with a main and an auxiliary interrupting means, and an operating lever associated with each interrupting means, of a pivotally mounted bell-crank lever having two arms respectively disposed substantially at right angles to each other and normally in horizontal and vertical planes, links for connecting the main interrupting means with the said horizontally disposed arm and the auxiliary means with the vertically disposed arm, and means for actuating the said bell-crank lever. 20
10. In a circuit interrupter, the combination with a main and an auxiliary interrupting means, and an operating lever associated with each interrupting means, of a pivotally mounted bell-crank lever having two arms respectively disposed substantially at right angles to each other and normally in horizontal and vertical planes, links for connecting the main interrupting means with the said horizontally disposed arm and the auxiliary means with the vertically disposed arm, and resilient means for actuating the said bell-crank lever in one direction. 25
11. In a circuit interrupter, the combination with a main and an auxiliary interrupting means, and an operating lever associated with each interrupting means, of a pivotally mounted bell-crank lever having two arms respectively disposed substantially at right angles to each other and normally in horizontal and vertical planes, links for connecting the main interrupting means with the said horizontally disposed arm and the auxiliary means with the vertically disposed arm, and means for restraining the bell-crank lever, and a spring for actuating the said bell-crank lever in one direction. 30
12. In a circuit interrupter, the combination with a main and an auxiliary interrupting means, and an operating lever associated with each interrupting means, of a pivotally mounted bell crank lever having arms respectively disposed in substantially horizontal and vertical planes, a plurality of links severally connecting the main interrupting means with said horizontally disposed arm and the auxiliary means with the vertically disposed arm, and means for actuating said bell crank lever. 35
- In testimony whereof, I have hereunto subscribed my name this 20th day of June, 1911.
